(57) **CLAIM**

The ornamental design for a wireless electronic pet fence system, as shown and described.

DESCRIPTION

FIG. 1 is a front, right, and top perspective view of a wireless electronic pet fence system, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled **9** in FIG. 1 comprising a part of a side wall; and,

FIG. 10 is a partial enlarged view of an area labeled **10** in FIG. 1 comprising a connection part of an antenna and a body part of the wireless electronic pet fence system.

The broken lines shown in the drawings are included for the purpose of illustrating portions of the wireless electronic pet fence system that form no part of the claimed design.

1 Claim, 10 Drawing Sheets
